UNITED STATES PATENT OFFICE.

NORMAN R. SIMPSON, OF ELIZABETH CITY, NORTH CAROLINA, ASSIGNOR OF ONE-SIXTEENTH TO NEWTON A. JONES, TWO-SIXTEENTHS TO JOHN C. OVERMAN, AND FIVE-SIXTEENTHS TO MARION M. HARRIS, ALL OF ELIZABETH CITY, NORTH CAROLINA, AND FOUR-SIXTEENTHS TO CARROLL B. SPENCER, OF SWANQUARTER, NORTH CAROLINA.

ELECTRIC STARTER FOR AUTOMOBILES.

1,292,110.

Specification of Letters Patent.

Patented Jan. 21, 1919.

Application filed December 22, 1916. Serial No. 138,448.

To all whom it may concern:

Be it known that I, NORMAN R. SIMPSON, a citizen of the United States, residing at Elizabeth City, in the county of Pasquotank 5 and State of North Carolina, have invented new and useful Improvements in Electric Starters for Automobiles, of which the following is a specification.

This invention relates to internal combustion engines, and more especially to starting devices; and the object of the same is to provide the fly wheel of an engine of this kind with an electric motor by means of which the fly wheel can be rotated and the 10 engine started when desired, by closing a circuit through a battery carried somewhere on the vehicle. After the engine is running, the motor generates electricity which recharges the battery in a manner which 15 will be clear.

Details of construction are set forth in the following specification and illustrated in the accompanying drawings wherein—

Figure 1 is a general side elevation of the 20 engine of a motor vehicle and the fly wheel thereof containing the starter.

Fig. 2 is an enlarged elevation of the fly wheel, partly in section, and

Fig. 3 is a still further enlarged detail 25 taken on the line 3—3 of Fig. 2, while

Fig. 4 is a radial section taken on about the line 4—4 of Fig. 2.

Fig. 5 is a sectional detail showing how the ends of the ring-parts may be brought 30 together and fastened.

Fig. 6 is a diagram showing the wiring.

The engine is broadly designated by the letter E in Fig. 1 and the frame by the letter F, the fly wheel W being here mounted on 35 the main shaft M in the rear of the engine as usual. Referring now to Fig. 4, the rim of the fly wheel W is rabbeted around its front corner as at 1, and within the rabbet is fixed a ring 2 provided with a dovetailed channel 3 in which is seated a ring 4 of insulation material such as hard rubber. In this ring at intervals are placed commutator segments 5 which project beyond the front face of the wheel-rim. In the illustration herewith there are sixteen of these segments as best seen in Fig. 2, and I prefer to use about that number when there are four pole pieces in the field as hereinafter de-

scribed. However, I do not wish to be limited in this particular. Around the periphery 55 of the wheel is a two-part ring 6, the ends of the two parts being shown in Fig. 5 as having outturned ears 7 connected by a bolt or rivet 8, and the entire ring being detachably mounted on the rim of the wheel by 60 tightening up on said bolts 8, although when they are loosened of course the ring can be removed. Carried by said ring at intervals corresponding to the spacing of the segments 5 are pole pieces 10, each preferably removably secured to the ring by means such as the screws 11 in Fig. 4; and in the same view the numeral 12 designates the winding of the coil, while 13 is the terminal wire leading from such coil to the segment 5. So 65 70 much of the mechanism as has been described is carried by and rotated with the fly wheel.

Referring now to Fig. 2, the numeral 20 designates a ring considerably larger than the fly wheel and entirely surrounding and 75 spaced from the same, and this ring has lugs 21 at opposite points by means of which it may be supported from the frame F. This ring carries four field magnets, one of which is shown in section in this view. The numeral 22 designates a fixed pole or block, held to the ring by suitable means such as a screw 23, and 24 is the coil surrounding this block. Disposed between these pole pieces are the brushes herein shown as consisting of 80 carbon blocks 25 resting against the commutator segments 5 as the latter revolve, the blocks being borne inward by suitable means as spring contacts 26 connected with binding posts 27 as seen in Fig. 3. By preference 85 each block moves in a guide 28 at the inner end of a bracket 29 which is mounted on the rings 20, and when the block 25 becomes worn it may be taken out of the guide and replaced by another. It will not be necessary 90 for the purposes of this specification to amplify the wiring further than as illustrated in diagram in Fig. 6 wherein B designates a battery on the body of the car, and S a circuit closer or switch of the usual type. 95 100

With this improved electric motor constructed in substantially the manner described and mounted on the fly wheel of an internal combustion engine, when it is desired to start the same, the operator has but 105 to close the switch S and complete the cir-

cuit from the battery B to the motor so that the latter starts at once and quickly, silently, and powerfully turns the fly wheel W and the main shaft M of the engine E, until the 5 latter commences to run on its own energy; and then the operator opens the switch and cuts out the motor. It is quite possible, however, to arrange the wiring in such manner that this switch may be left closed or may 10 be thrown onto a shunt winding so that after the engine is running the rotation of the fly wheel and motor will recharge the battery B; but as this forms no part of the present invention I have not illustrated the details 15 thereof. Nor have I shown the battery except in diagram at B in Fig. 6, but it is clear that this battery must be of sufficient size and power to generate enough energy in the motor to turn over the main shaft M against 20 the resistance set up by the compression in the cylinders of the engine. However, with my motor built into a fly wheel of the usual size on automobiles, it will ordinarily have sufficient pulling power to start an engine 25 where the compression is not excessive. While I propose to build this starter as part of the equipment of automobiles when made in the factory, it is quite possible to apply it to an automobile already on the market 30 and in use. In that case, however, it would doubtless be preferable to omit the rabbet 1 and attach the ring 2 directly to the forward side of the rim W of the wheel by some other means such as will readily suggest them- 35 selves. The ring 6 of course being made in two parts can be slipped over the flat periphery of the rim W and drawn tightly thereon by setting up the bolts 8. In some makes of automobiles there is a hood or

drum surrounding the fly wheel, and this of course will have to be removed or enlarged sufficiently to permit the entry of the ring 20 and the parts carried thereby. Otherwise there is no change to the structure of the automobile or the engine, and this starter may 45 be applied and used without the introduction of any gearing or belting, chains or clutches, levers or controls, except the ordinary battery B and switch S. 50

What is claimed as new is:—

1. In a motor for use as an engine starter, a rotor comprising a revolving element and a ring mounted thereon, said ring being secured upon the periphery of said revolving element and comprising two parts adapted to be clamped thereon, the extremity of each part being formed with outturned ears, the ears at the abutting ends of the parts being arranged adjacent each other, and bolts engaging the contacting ears for drawing the ring into holding contact with the periphery of the revolving element. 55

2. In a motor for use as an engine starter, a revolving element rabbeted in its front face, a ring set into said rabbet and formed with a dovetailed channel, insulation within said channel, commutator segments held within the channel and against the ring by the insulation, said ring having a laterally extending portion comprising two parts to engage the periphery of the revolving element, and means for clamping said parts to secure them on the element. 65 70

In testimony whereof I affix my signature.
NORMAN R. SIMPSON.
